UNITED STATES PATENT OFFICE.

ARTHUR R. MOSLER, OF NEW YORK, N. Y., ASSIGNOR TO A. R. MOSLER & CO., OF YONKERS, NEW YORK, A CORPORATION OF NEW YORK.

SPARK-PLUG.

1,218,298.

Specification of Letters Patent.

Patented Mar. 6, 1917.

Application filed November 14, 1912. Serial No. 731,321.

To all whom it may concern:

Be it known that I, ARTHUR R. MOSLER, a citizen of the United States, and resident of the borough of Manhattan, in the city and 5 State of New York, have invented a new and useful Improvement in Spark-Plugs, of which the following is a specification.

This invention relates to spark plugs, and more particularly to the assembly of the insulating block, central electrode and binding 10 post.

The objects are to produce an arrangement of this character which is extremely cheap and yet entirely satisfactory in operation.

15 Another object is to provide an arrangement whereby the electrode is secured in the insulating block in such a manner as to prevent the possibility of gas leakage about the electrode and through the block.

20 Other objects are to provide certain improvements in the construction, form and arrangement of the several parts whereby the above mentioned objects may be effectively carried out.

25 A practical embodiment of the invention is represented in the accompanying drawings, in which,

Figure 1 represents a side elevation of 30 the parts in their assembled position.

Fig. 2 represents a vertical central section of the same.

Fig. 3 represents an end view of the same.

35 Fig. 4 represents a section taken in the plane of the line A—A of Fig. 1, looking in the direction of the arrows.

Fig. 5 represents a section taken in the plane of the line B—B of Fig. 1, looking in the direction of the arrows.

40 Fig. 6 represents a section taken in the plane of the line C—C of Fig. 1, looking in the direction of the arrows.

Fig. 7 represents a side elevation of the cap and binding post.

45 Fig. 8 represents a bottom plan view of the same.

Fig. 9 represents a side elevation of the electrode with the packing ring loosely wound thereon.

50 Fig. 10 represents a side elevation of the insulating block, and

Fig. 11 represents a side elevation of a modified form of electrode with the packing ring loosely wound thereon.

55 The insulating block is denoted by 1, and

may be of any convenient or desired shape. It is preferably provided with a longitudinal hole, one part of which is of greater cross section than the other part, as clearly shown in Fig. 2. The electrode, commonly carried 60 by the insulating block, has a portion 2 of relatively small cross section, and a portion 3 of relatively large cross section. The cross sectional size of the electrode is such that its smaller portion will loosely fit in 65 the smaller portion of the hole in the insulating block 1, while its larger portion will have a correspondingly loose fit in the larger part of the said hole.

The electrode is secured in the insulating 70 block by means of some adhesive material, such for instance as cement, 4, and in order to cause the cement to firmly grip the electrode, the latter is screw-threaded or otherwise roughened, as indicated at 5.

75 A packing ring 6 may conveniently be located between the enlarged portion of the electrode and the base of the enlarged portion of the hole in the insulating block.

80 A cap 7 is arranged to fit the outer end of the insulating block 1, and carries a suitable binding post 8, which may be conveniently secured in the cap 7, by squaring the end of the binding post 8, and fitting this squared end into the corresponding opening 85 in the cap 7, and up-setting or riveting the said end of the binding post. This cap 7 is provided with a longitudinal, inwardly extending tongue 9 arranged to snugly fit in a corresponding groove 10 in the top of 90 the insulating block 1, to prevent the cap from turning on the block; while the insulating block is provided, near its upper end, with a shoulder 11, about which the lower edge of the cap 7 may be crimped, as clearly 95 shown at 12 in Fig. 2, for the purpose of firmly securing the cap against longitudinal movement on the block. The tongue 9 on the cap 7, by reason of its snug engagement with the groove 10 in the insulating block, 100 will enable a cap which would otherwise fit loosely on the block, to be held firmly in position against wobbling.

105 For making electric connection between the electrode and the binding post 8, the upper end of the insulating block 1 is covered with some adhesive material such for instance, as cement, which is impregnated with comminuted metal, such as iron filings. It will be seen that when the cap 7 is firmly 110

- forced down on to the insulating block 1, this comminuted metal will form electric connection between the enlarged end 3 of the electrode and the base of the binding post 5. The cement impregnated with this comminuted metal, is clearly shown at 13 in Fig. 4.
- Referring to the modified form shown in Fig. 11, the electrode may be made of uniform cross section, but be provided with an abutment 14 arranged to engage the bottom of the enlarged portion of the hole in the insulating block 1, with the interposition of the previously referred to packing ring 6. 10
- In assembling this portion of the spark plug, it is only necessary to pour cement in the hole in the insulating block, loosely coil the packing ring about the lower portion of the electrode, as clearly shown in 15
- Figs. 9 and 11, and then force the electrode into the insulating block. This action will cause the enlarged portion of the electrode or the abutment 14 to crowd some of the cement down into the smaller portion of 20
- the hole in the insulating block and thus insure that the entire space between the electrode and the block is filled with the cement. The top of the insulating block is covered with cement into which is forced 25
- a quantity of comminuted metal, after which the cap 7 carrying the binding post 8, is forced down on to the insulating block and crimped about the shoulder 12.

It will be seen that this construction enables the insulating block and electrode to be very cheaply manufactured, no care being required to produce an accurate fitting, as the cement will fill in all the spaces between the relatively large or relatively small. 30

Furthermore, the cement acts as a very firm binding agent between the electrode and the insulating block and also as a positive gas check. 40

Also the provision of the comminuted metal in the cement at the end of the insulating block obviates the necessity of having an exact fit for providing suitable electric contact between the binding post and the electrode. 45

It is obvious that various changes might be resorted to in the construction, form and arrangement of the several parts without departing from the spirit and scope of my 50

invention; hence I do not wish to limit myself strictly to the structure herein set forth, but

What I claim is:

1. In a spark plug, a one piece insulating block provided with a longitudinal hole therethrough, a shoulder in the said hole, 60

an electrode provided with an abutment, the said electrode being surrounded by cement for holding it securely in the hole in the said block with its abutment substantially against the said shoulder, and a packing ring between the shoulder and the abutment. 65

2. In a spark plug, a one piece insulating block provided with a longitudinal hole therethrough, one portion of said hole being of greater cross section than the remainder, an electrode located in said hole and having one portion of greater cross section than the remainder, its larger part and smaller part being of appreciably less cross section than the corresponding parts of the hole, and a layer of cement surrounding the electrode within the hole for securing the electrode in the block. 70

3. In a spark plug, an insulating block, 80 an electrode therein, a cap for the block carrying a binding post, and comminuted metal adhesively secured between the cap and block for making electric connection between the binding post and electrode. 85

4. In a spark plug, an insulating block, an electrode therein, a cap for the block carrying a binding post, and comminuted metal cemented between the cap and block for making electric connection between the binding post and electrode. 90

5. In a spark plug, an insulating block, an electrode cemented therein, a cap for the block carrying a binding post, and a layer of cement between the cap and the block, 95 the said layer being impregnated with comminuted metal for making electric connection between the electrode and binding post.

In testimony, that I claim the foregoing as my invention, I have signed my name, 100 in presence of two witnesses, this 30th day of October, 1912.

ARTHUR R. MOSLER.
